UNITED STATES PATENT OFFICE.

ROBERT TINSLEY, OF CHICAGO, ILLINOIS; ASSIGNEE TO THE PULLMAN COMPANY, OF CHICAGO, ILLINOIS, A CORPORATION OF ILLINOIS.

WALL CONSTRUCTION.

993,127.

Specification of Letters Patent. Patented May 23, 1911.

Application filed June 6, 1910. Serial No. 565,194.

To all whom it may concern:

Be it known that I, ROBERT TINSLEY, a citizen of the United States, residing at Chicago, in the county of Cook and State of Illinois, have invented certain new and useful Improvements in Wall Constructions, of which the following is a specification.

This invention relates to wall constructions and aims to produce a substantial and durable wall particularly adapted for railway cars in general, and more particularly for railway baggage cars.

The walls of baggage cars, particularly the inner walls are subjected to very hard usage in the transportation of baggage, due to the corners of large and heavy trunks and boxes striking and falling against them and the frequency with which the wooden walls of comparatively new baggage cars were split and broken in this manner has led to the general adoption of sheet metal lining for the cars. Flat sheet metal, however, is very easily dented and bent, and in order that it might be stiff enough to withstand the shocks and concussions incident to the handling of baggage, it has heretofore been necessary to make the metal lining very thick and heavy. In addition to increasing the initial cost of the cars because of the expensiveness of heavy sheet metal, the walls constructed of heavy metal increase the weight of the cars, thereby unnecessarily increasing the cost of hauling them.

It is an object of my present invention to provide a car wall construction for use in baggage cars which will be light in weight and at the same time strong and durable, and which will not be readily bent or dented.

Another object is to provide a sheet metal wall having straps or protecting strips extending longitudinally thereof on its inner face, which serves the dual purpose of securing the metal sheet in place and affording protection to its inner surface.

An additional object of the invention is the provision of a wall or wall lining which can be readily placed in position after the car is assembled, and which can be easily removed and replaced or repaired as occasion requires.

Still another object is the provision of improved means for removably securing the metal sheet and straps to the vertical wall posts.

The invention has other objects and ad-

vantages which will be readily understood from the following description when taken in connection with the accompanying drawings illustrating a preferred embodiment thereof, in which—

Figure 1 is an elevation of a section of the inner face of a wall embodying my invention. Fig. 2 is a vertical section thereof. Fig. 3 is an enlarged detail view showing the manner of fastening the wall to a post. Figs. 4, 5, 6 and 7 show modified forms of the upright posts; and, Fig. 8 is a fragmentary elevation showing one of the bolt receiving openings with which the posts are provided.

On the drawings, 9 indicates a side sill of a car, which may be made in any of the well known and usual forms carrying the floor 10 and having secured thereto the upright posts 11, by the usual rivets or bolts 12. The outer wall 13 of the car may be secured to the upright posts in any preferred manner, depending to a considerable extent upon the shape of the posts employed.

In Figs. 2 and 3, the post 11 is shown simply as an angle-bar. In Fig. 4 I have shown a modified form of post 14 which is of Z-bar formation. Another modification 15 is disclosed in Fig. 5 which is constructed in an L-shape. Fig. 6 illustrates another modification showing a post 16 constructed in the form of a channel-bar; and Fig. 7 shows still another modification of a post 17 of T-bar configuration. It will be obvious that many other forms of post might be employed, the only feature which is material to this invention residing in the fact that the inner edge of the post should provide a substantially flat face extending transversely of the post which can be provided with a bolt receiving opening 18.

An enlarged view of the bolt receiving opening 18 is shown in Fig. 8, from which it will be seen that the opening comprises a circular part 19 of sufficient size to receive the head 20 of a bolt, and is extended at its lower side into a substantially square slot 21 to accommodate the square shank 22 of the bolt to prevent the bolt from turning in the opening.

Upon the inner faces of the upright posts there is disposed a sheet of corrugated metal having the corrugations preferably extending in a vertical direction parallel with the upright posts. The sheet may be made of

sufficient size to cover one wall of a car or it may be made in sections of any preferred size and shape adapted to be placed in position to form a complete covering or lining 5 for the vertical walls of the car. A plurality of metal straps or strips 24 is disposed transversely of the corrugations and of the upright posts upon the inner surface of the corrugated sheet. The straps are bent at intervals throughout their length, spaced to correspond to the spacing of the upright posts to provide depressions 25. These depressions, as will be evident from Fig. 3, are adapted to fit in the depressions in the 10 surface of the corrugated sheet. The depressed portions of the straps are provided with bolt receiving openings adapted to be alined with the bolt holes or openings 18 in the posts. The sheet 23 is also provided with bolt receiving openings spaced to be alined with the bolt holes or openings in the posts. The fastening bolts designated generally as 26, project inwardly from the inner face of the post through the corrugated sheet 23 and the 15 straps 24. A washer 27 is preferably positioned upon the bolt between the corrugated sheet and the strap to firmly bind the sheet to the post when the fastening nut 28 is threaded upon the bolt.

30 It will be evident from the above description that the car may be assembled with the upright posts in position and the outer walls of the car fixed in place before the lining or metal sheet is attached in position.

35 When the posts are of such shape that it is inconvenient to insert the fastening bolts from the rear of the flange, the head 20 of the bolt may be inserted through the enlarged portion 19 of the bolt receiving openings in each post, and the shoulder 22 thereof engaged in the angular slot 21. The corrugated sheet 23 or sections thereof may now be slipped over the projecting ends of the 40 bolts, the washers 27 are placed upon the bolts, the straps 24 are engaged with the bolts, and the fastening nuts 28 are screwed up to firmly clamp the sheet and straps to the posts. The corrugated sheet is stronger than a plain sheet of the same weight and 45 is lighter than a plain sheet of the same strength. The straps which are spaced apart vertically of the car, serve as a protection to the inner face of the sheet as well as to maintain the sheet in position. The 50 depressed portions 25 of the straps fit into the depressions in the corrugated surface of the metal sheet and provide a more rigid engagement between the straps and sheet, and also render possible a construction in 55 which the nuts or the bolts are readily accessible on the inside of the car but in which the ends of the bolts or nuts thereon do not project into the car beyond the inner face of the wall.

60 65 It will be evident from the above that the

corrugated sheet or section thereof may be removed as occasion should require, to be repaired or replaced by a new sheet or section without dismantling the car or disturbing the outer walls thereof. It will also be evident that the construction is capable of considerable variation in structural details from the modification disclosed, without departing from the spirit of the invention or sacrificing any of the material advantages thereof, 70 therefore, I do not wish to be limited to the exact construction shown and described, but believe I am entitled to all such variations thereof as properly come within the 75 scope of the appended claims.

What I desire to claim is:

1. In a wall construction, the combination of upright posts, a metal sheet disposed against the posts, metal straps arranged on the inner face of said sheet, said straps being provided with depressed portions spaced to coincide with the said posts, and bolts extending through said posts, metal sheet and the depressed portions of the straps, for rigidly securing said sheet and straps to the 85 posts.

2. In a wall construction, the combination of upright posts, a metal sheet disposed against the posts, metal straps arranged on the inner face of said sheet, the posts being provided with openings through which a head of a bolt may be passed, the openings being extended into a smaller angular portion to receive the shank of the bolt and prevent turning of the same, and a bolt engaged in said opening and extending through the metal sheet and strap, whereby the sheet and strap are secured to the post.

3. In a wall construction, the combination of upright posts, a corrugated metal sheet 95 disposed against the posts, a plurality of metal straps having depressed portions adapted to fit into corrugations in the sheet and spaced apart to coincide with the upright posts, and means for connecting the 100 sheet and straps to the posts.

4. In a wall construction, the combination of a plurality of upright posts, a metal sheet vertically corrugated, positioned against the inner faces of said posts, a plurality of metal straps disposed transversely of the posts and corrugations in the sheet, each strap being provided with spaced apart depressions each having a bolt receiving hole therein, and a plurality of bolts adapted to be engaged with the posts from the inner side thereof and extending inwardly from the posts through said sheet and straps, whereby the said sheet and straps are fixedly secured to the posts.

5. In a wall construction, the combination of a plurality of upright posts, each provided with a flange along its inner edge and having bolt receiving openings in the flange adapted to permit the head of a bolt to be 115 120 125 130

inserted therethrough from the inner side and to hold said bolt against turning movement in the opening, a corrugated metal sheet disposed against the inner faces of the 5 posts, a plurality of metal straps arranged transversely of the posts along the inner face of the said sheet, said straps being provided with depressed portions provided with openings adapted to be alined with the openings in the posts, and a plurality of bolts 10 projecting inwardly from the posts through the corrugated sheet and the straps, for fastening the sheet and straps to the posts.

6. In a railway car-wall construction, the 15 combination of a plurality of apertured up-

right posts, a corrugated metal sheet disposed against the inner faces of said posts and provided with apertures spaced to conform to the spacing of said post apertures, apertured metal straps arranged on the inner face of said sheet, and bolts extending through the apertures of said posts, metal sheet and straps, for rigidly and detachably securing the sheet and straps to the posts, substantially as described. 20
